UNITED STATES PATENT OFFICE.

CARL BOMEISLER, OF NEW YORK, N. Y.

DESIGN FOR A CORN-HOLDER.

No. 39,815.

Specification for Design.

Patented Feb. 9, 1909.

Application filed November 18, 1908. Serial No. 463,327. Term of patent 7 years.

To all whom it may concern:

Be it known that I, CARL BOMEISLER, a citizen of the United States, residing at the city of New York, borough of Manhattan, in the county and State of New York, have invented a new, original, and ornamental Design for a Corn-Holder, of which the following is a specification, reference being had to the accompanying drawing, forming part thereof, in which—

Figure 1 is a side view showing a corn-holder incorporating my said design, and Fig. 2 is a top view thereof.

In said drawings the holder is shown comprising a handle portion representing an ear of corn having its upper end terminating in a smooth outwardly flaring portion; a bolster extending from said end having inwardly and

outwardly curved side surmounted by a flat, circular base from the center of which extends a prong or blade. The body portion of said prong or blade has slightly tapering sides which merge with the point of said prong or blade. Both the body portion and said point have their edges beveled, and upon opposite sides of said prong or blade are tapering triangular ribs diminishing in size from the base of said prong or blade towards the point thereof.

I claim—

The ornamental design for corn-holder, as herein shown and described.

CARL BOMEISLER.
